UNITED STATES PATENT OFFICE

162,745

COMB

Peter Morroni, Leominster, Mass.

Application November 7, 1949, Serial No. 5,907

Term of patent 3½ years

(Cl. D86—8)

To all whom it may concern:

Be it known that Peter Morroni, a citizen of the United States, residing at Leominster, in the county of Worcester, State of Massachusetts, has invented a new, original, and ornamental Design for a Comb, of which the following is a specification, reference being had to the accompanying drawing, forming part thereof.

Fig. 1 is a front elevational view of the comb showing my new design;

Fig. 2 is a cross sectional view taken on line 2—2 of Fig. 1;

Fig. 3 is a cross sectional view taken on line 3—3 of Fig. 1.

The reverse side is the same as the side shown.

The dominant feature of my design resides in that portion shown by means of full lines in the drawing.

I claim:

The ornamental design for a comb, as shown and described.

PETER MORRONI.
